TWO-STAGE HYDRAULIC PRESSURE PUMP

Bernard Beaman, Julius Hulman, and
Robert A. Stein, Dayton, Ohio

Application June 8, 1945, Serial No. 598,356

17 Claims. (Cl. 103—5)

(Granted under the act of March 3, 1883, as
amended April 30, 1928; 370 O. G. 757)

1
The invention described herein may be manufactured and used by or for the Government for governmental purposes without the payment to us of any royalty thereon.

Our present invention relates to a hydraulic pressure pump of two-stage character which is designed for efficient operation at extremely high pressures in the second stage.

One object of the invention is to provide a two-stage pump which is compact, the design being simple and involving but few parts which can be readily fabricated and assembled.

Another object is to provide a pump wherein loaded bearings are minimized, the thrust forces being taken by stationary thrust surfaces.

Still another object is to provide a pump wherein effective seals against fluid loss may be provided in a simple manner.

Still another object is to provide a first-stage pump of sliding vane type and a second-stage pump comprising a rotating barrel having cylinder bores therein with pistons provided in the bores and slideable by a cam.

A further object is to floatingly mount the barrel so that it will effectively seat against an end plate of the pump under the force of internal pressure acting on partially closed cylinder bore ends, and to provide a relief valve for such pressure to maintain it at a desired value somewhat lower than the pressure in the high pressure side of the pump without exceeding such desired pressure.

Still a further object is to provide a two-stage pump wherein the mechanism of two pumps in series is built into one housing to form a compact, self-contained unit.

An additional object is to provide a high pressure piston pump which is pressurized by a low pressure vane pump, the vane pump overfeeding the piston pump and having a pressure relief means from the outlet of the vane pump to the inlet thereof to thus maintain a predetermined charging pressure for the piston pump and to force the pistons therein against a cam without the necessity of providing return springs, linkage or some other mechanical means for this purpose.

A further additional object is to provide a structure which can be rotated in one direction for pumping liquid, an arrangement being provided for reversing the vane pump within the

2
housing in the event that it is desirable to reverse the direction of rotation of the pump shaft.

Still a further additional object is to provide a pump structure wherein an increased pressure thrust of a cylinder barrel against a valve plate is secured by reducing the unseating pressure force on the area between the barrel cylinder openings and the barrel land area, such construction involving a valve port diameter less than the cylinder circle diameter and permitting of multiple drilled passageways from the ends of the cylinders to the valve ports so that the flow area can be made the desired value and the drilled passageways being at an angle, thus producing an elliptical intersection between the drilled passageways and the valve ports.

With these and other objects in view, our invention consists in the construction, arrangement and combination of the various parts of our pump structure whereby the objects contemplated are attained, as hereinafter more fully set forth, pointed out in our claims and illustrated in the accompanying drawings, wherein:

- Fig. 1 is a front elevation of our pump;
- 25 Fig. 2 is a rear elevation thereof;
- Fig. 3 is a vertical sectional view on the line 3—3 of Fig. 2;
- 30 Fig. 4 is a horizontal sectional view on the line 4—4 of Fig. 3;
- Fig. 5 is a sectional view on the line 5—5 of Fig. 4 showing the pistons in the cylinder bores of the high pressure pump;
- 35 Fig. 6 is a sectional view on the line 6—6 of Fig. 4 showing a portion of the porting arrangement;
- Fig. 7 is a sectional view of the line 7—7 of Fig. 6 showing further details of the porting arrangement;
- 40 Fig. 8 is a sectional view on the line 8—8 of Fig. 4 showing the low pressure pump;
- Fig. 9 is a sectional view on the line 9—9 of Fig. 4 showing a reversing arrangement for the low pressure pump;
- 45 Fig. 10 is an end view of a portion of Fig. 9 looking in the direction of the arrow 10 adjacent thereto;
- Fig. 11 is a sectional view on the line 11—11 of Fig. 9 showing further details thereof;

Fig. 14 is a front view of the pressure relief valve shown in Figs. 12 and 13, with the end plate of the housing left off to show the relationship of parts;

Fig. 15 is a sectional view of a modified construction wherein an arrangement of parts is provided for increasing pressure thrust of the barrel against the end plate of the pump; and

Fig. 16 is a sectional view on the line 16—16 of Fig. 15 showing the elliptical ends of drilled passageways of the construction shown in Fig. 15.

On the accompanying drawings we have used the reference numeral 10 to indicate a cylindrical housing. The housing has a flange 12 at one of its ends for mounting the pump on an engine or the like. For this purpose, bolts or screws may extend through perforations 14 of the flange and thread into the engine or any suitable support, in the usual manner. The housing 10 has a flange 16 at its other end to which an end plate 18 is secured, as by cap screws 20, with a suitable gasket or sealing compound between the flange and the end plate.

The housing 10 has an internal partition 22 against which a back plate 23 is positioned. A cam 24 is affixed thereto as by seven large screws 25 and three small screws 27. The cam fits the interior of the housing 10 and is retained against rotation by a pair of dowels 19 and 21 which will be more fully described later on in the specification. The cam 24 has a cam face 28 which is in the form of a truncated cylinder end, and a hardened creep plate 30 of washer-like character is engaged against this face.

Rotatable in bearing surfaces 32 and 34 in the end plate 18 and the cam 24, respectively, is a barrel drive shaft 36. Loosely splined at 42 on the barrel drive shaft 36 is a barrel 44 having an annular shoulder 46 engaging the shaft 36 for guide purposes. The barrel 44 has a flat sealing face 50 to contact with a flat sealing face 52 of the end plate 18. The loose splining of the barrel 44 to the shaft 36 permits ready conformity of the face 50 to the face 52.

Circumferentially spaced cylinder bores 54 are provided in the barrel 44, and in each a plunger-like piston 56 is reciprocable. Each cylinder has a cylinder port 58 of the shape shown in Fig. 5. The ports are of somewhat less cross-sectional area than the area of the cylinder bore in order to provide the necessary thrust force between the barrel 44 and the end plate 18 by internal pressure acting on the cylinder bore ends surrounding the ports 58. The cylinders 54 and the pistons 56 constitute a high pressure pump. The barrel 44 is adapted to be seated against the end plate 18 by pressure within the housing 10, as will hereinafter appear. During starting of the pump, when pressure has not yet built up, it is desirable to make sure that the faces 50 and 52 are in contact, and this may be accomplished by a light spring 59, as shown in Figs. 4 and 5.

A low pressure pump is provided in the form of a rotor 38 having slots 40 in which vanes 48 are slidably mounted, as shown in Fig. 8. The rotor 38 is within a stator bore 60 of the cam 24, which stator bore is eccentric with relation to the rotor to thereby effect inward and outward movement of the vanes 48.

A low pressure inlet boss 62 is provided on the end plate 18, as shown in Figs. 2 and 4. This boss communicates with a passageway 64 in the end plate which, in turn, communicates with an in-

take passageway 66 in the housing 10. The passageway 66, as shown in Fig. 4, communicates with the interior of the dowel 21 through openings 68 therein, and the interior of the dowel communicates with an intake port 70 formed in the back plate 23. This port feeds liquid into the intake side of the low pressure pump (the left side in Fig. 8).

An outlet port 72 is provided on the high pressure side of the low pressure pump, and this outlet communicates through openings 74 in the dowel 19 with an outlet passageway 76 (see Fig. 4). The passageway 76 extends to the inner face 52 of the end plate 18 and communicates with a C-shaped passageway 78 formed in the end of the housing 10 adjacent the plate 18, as shown in Fig. 5. The ends of the C-shaped passageway 78 communicate with a pair of passageways 80 which are best shown in Figs. 6 and 7, for conducting the liquid back toward the center of rotation into an arcuate intake port 82 formed in the end plate 18. The passageways 80 are also formed in this end plate, as clearly shown in Fig. 7.

The arcuate intake port 82 is provided for the high pressure pump, and the cylinder ports 54 thereof successively register with the port 82 and a similar arcuate outlet port 84 which communicates directly with an outlet or high pressure boss 86 on the end plate 18. The boss 86 is the outlet and the boss 62 is the intake, and, accordingly, there is low pressure in the boss 62 and high pressure in the boss 86, as indicated by the legend "HI" and "LO" in Figs. 2 and 4.

The dowel 19 is threaded in position and can accordingly be removed. The dowel 21 is also removable, it normally being retained in position by a ring-like plug 88 which, in turn, is threaded into the housing 10. The ring-like plug has a hexagonal socket for convenience in removing it. The dowel 21 has a lug 90 received in a notch 92 of the back plate 23. The outer end of the dowel 21 has an arrow 94 thereon to indicate the direction of rotation for the pump.

The housing 10 has a pair of keyways 96 and 98 to selectively receive the lug 90, and the back plate 23 has a second notch 100, similar to the notch 92. It also has a serrated circumference indicated at 102 for reversing purposes as will hereinafter appear.

The rotor 38 is formed on a shaft 104 which rotates in a bearing surface 106 of the back plate 23 as shown in Figs. 4 and 5. It is connected to the barrel drive shaft 36 by a loosely splined connection 108 and with a drive shaft 110 by means of a loosely splined connection 112. The drive shaft 110 has a splined end 114 for connection to a power take-off shaft of an aircraft engine or any other suitable means to drive the pump. Such means would align the outer end of the drive shaft 110 for proper operation without binding.

The drive shaft 110 has a flange 116 surrounding it, with which a seal plate 118, in the form of a ring, is engageable. A spring 120 effects such engagement initially, whereas fluid pressure within the housing effects the engagement after the pump is in operation, as will hereinafter appear. The spring 120 is seated against a second end plate 122 secured to the partition 22 by suitable means such as screws 124.

The seal plate 118 is sealed relative to the housing 10 by means of a diaphragm 126 having its inner edge clamped to the seal plate by a spanner nut 128 and its outer edge clamped between a washer 130 and the end plate 122.

by screws 124. This provides a pressure chamber, indicated at 132, inside of the flange 116.

The inner end of the drive shaft 110 is seated against a shoulder 134 of the rotor shaft 104 which serves merely as a thrust connection, but, normally, when the pump is operating, the two are spaced from each other. A passageway 138 is provided through the center of the rotor shaft and communicates with a passageway 138 through the center of the barrel shaft through which liquid is adapted to flow after passing through the splined connections 112 and 108. A relief groove 140 is provided for such flow in the event that the inner end of the drive shaft 110 is seated against the shoulder 134.

The passageway 138 communicates with a pressure relief valve in the form of a valve plug 142 seated against a ring 144 by a spring 146. The valve plug acts as a piston in a sleeve 148 which serves to guide its sliding movement. The sleeve 148 has a head 150 for screwing the sleeve into the end plate 18 at a screw-threaded connection 152. The sleeve 148 has ports 154 communicating with an annular groove 156 which, in turn, communicates by means of a passageway 158 with the low pressure boss 62.

The low pressure pump comprising the rotor 38 and the vanes 48 is of higher capacity than the high pressure pump comprising the cylinders 54 and the pistons 56. This is for the purpose of assuring full charging of the high pressure cylinders for reducing voids in the liquid and for keeping the pistons in contact with the creep plate 30. To avoid excessive build-up of pressure and to keep a substantially even charging pressure from the low pressure pump to the high pressure pump, a relief valve from the outlet of the low pressure pump to its inlet is provided. This is shown in Figs. 12, 13 and 14 and consists of a sleeve 160 in a bore 162 between the intake passageway 66 for the low pressure pump and the high pressure passageway 78. The position of this bore is best shown in Fig. 5. Referring to Fig. 13, it will be noted that there is a pair of annular grooves 164 and 166 surrounding the sleeve 160, and passageways 168 and 170 serve to communicate these grooves with the passageways 66 and 78, respectively.

Within the sleeve 160 is a differential pressure plunger having a large portion 172 and a small portion 174 so that the liquid under high pressure from the low pressure pump acts on the bottom of the plunger portion 172 to raise it against the action of a spring 176. The spring is retained in position by a retainer ring 178, and the entire relief valve assembly is held in position by the end plate 18 when it is installed. The operation of this valve will be referred to hereinafter.

In Figs. 15 and 16 we have shown a modified construction wherein the cylinder barrel 44, instead of having ports 58 drilled axially with respect to the cylinders, has a pair of ports 58^a drilled at an angle relative thereto and thus terminating in elliptical port openings 58^b, as shown in Fig. 16, closer to the center of rotation than the axes of the cylinders 54. This provides increased pressure thrust of the barrel against the valve plate as it reduces the unseating pressure force on the area between the barrel cylinder openings and the barrel land area. This is basically produced by reducing the radii of the ports 82 and 84 in the end or valve plate 18, their diameter thus being less than the cylinder circle diameter. Fig. 15 clearly shows the ports

58^a drilled at an angle, and any number may be used (two are shown by way of illustration) per cylinder, as required to provide the desired flow passage. The barrel is preferably provided with a pair of circular lands 44^a and 44^b, the land 44^a being in alignment with the cylinder circle diameter and acting as a stabilizing land. The land 44^b for the ports 58^b, 82 and 84, it will be noted, is brought inside the cylinder circle diameter.

Practical operation

The shaft 110 is driven by any suitable power means to thereby drive the rotor shaft 104 and the barrel shaft 36. The rotor 38 and the barrel 44 are thereby driven, and rotation of the rotor causes liquid to be drawn in from the intake boss 62 through the passageways 64, 66, 68 and 70 to the low pressure pump. The liquid therein is pumped out through the passageways 72, 74, 76, 78, 80 and 82 to the pistons 56 on their inward strokes while their cylinder ports 58 communicate with the end port 82.

Rotation around the other half of the circle causes the pistons to be forced outwardly in the cylinders 54 for forcing the oil into the high pressure outlet passageway 84 and the outlet boss 86. The liquid is thus pumped at low pressure by the vane pump and at high pressure by the piston pump which is charged by the low pressure vane pump, and the pressure in the outlet 86 may be relatively high, such as 3,000 pounds per square inch in the particular design of pump illustrated.

Since the vane pump overfeeds the piston pump, the relief valve, as shown in Fig. 13, will be opened by the liquid pressure overcoming the pressure of the spring 176 and thereby permitting the oil from the annular passageway 166 to enter the annular passageway 164, and find its way back to the intake side of the low pressure pump. Thus, a substantially even pressure of oil from the low pressure pump to the high pressure pump is maintained with assurance of full charging of the high pressure pump even after the pump becomes worn to some extent.

During operation the spring 59 keeps the barrel 44 in engagement with the end plate 18, and the spring 120 keeps the seal plate 118 in engagement with the flange 116 so that there is a sealed chamber within the housing 10 all the way from the end plate 18 to the diaphragm 126. These springs, particularly the spring 59, maintain the seal necessary for priming the pump. There is some leakage of liquid past the faces 50 and 52, especially before pressure is built up in the housing 10, and this liquid, together with the small amount which creeps past the pistons 56, and any which may leak from the low pressure pump, will charge the interior of the housing 10 for lubricating the bearing surfaces 32, 34 and 106, and producing pressure within the housing. The barrel 44 will be seated against the end plate 18 under the action of the charging pressure for the housing plus the internal pressure of the cylinder bores acting on the partially closed cylinder ends. The housing pressure also acts on the flange 80 to compress the spring 120 somewhat and thereafter maintain the flange 116 against the sealing face of the seal plate 118 under such pressure. The pressure is limited, however, by the relief valve 142, depending upon the strength of the spring 146. The liquid pressure will move the relief valve to a relief position, permitting the excess liquid to flow through the ports 154, 156 and 158 back to the low pressure

boss 62. A selected spring 146 may be used as required to keep a desired pressure within the housing. The valve 142 therefore acts as a pressure regulating valve.

Our two-stage pump can be readily adjusted for a reversal in the direction of rotation in the following described manner: The dowel 19 is unscrewed, and the plug 88 is unscrewed and the dowel 21 then pulled out. A screwdriver may now be inserted into the opening for the dowel 21 and engaged with the serrated periphery 162 of the back plate 23 for rotating the back plate a half turn. The housing 10 is cut away, as indicated at 99 in Fig. 9, to permit passage of the screwdriver for starting the rotation.

After the back plate has been rotated a half turn the notch 100 will occupy a position shown by dotted lines and indicated as 100a. The dowel 21 may now be reinserted but will have to be turned over a half turn so that the lug 90 will pass through the groove 98 and enter the notch 100 at the position 100a. This turns the arrow 94 (Fig. 10) to a position pointing up instead of down in order to indicate that the pump is now to rotate in the opposite direction. The plug 88 can be reinserted, the dowel 19 reinserted, and the stator bore 60 will be eccentric above the rotor 30 in Fig. 8 instead of below it. Thereupon, rotation of the pump is necessarily clockwise in Fig. 8 instead of counter-clockwise. The end plate 18 may remain in the same position.

From the foregoing specification we believe it will be obvious that we have provided a structure which compactly includes both a low pressure pump and a high pressure pump, whereby a complete hydraulic pump suitable for high pressure operation is had.

The design is such that there are few parts, and they are simple to form, machine and assemble. The necessary thrust of the rotating barrel to effect pressure seal is had without the necessity of providing the spring 59 other than for the purpose of the initial thrust before pressure is built up within the housing. The spring can therefore be comparatively light, yet will insure proper priming of the pump. The seal at 116-118 remains effective even if the shaft 110 is out of alignment or eccentric, or if the splines 108 and 112 should happen to stick.

The barrel 44 is fully floating on the barrel shaft so that it can properly seat against the end plate 18 without any binding whatever. The vanes in the low pressure pump are forced outwardly by centrifugal force, and the volume of liquid trapped between two adjacent blades alternately increases and decreases as the rotor turns, thereby giving the desired pumping action.

The inlet and outlet ports 70 and 72 are preferably overlapped slightly at their lower ends with respect to adjacent vanes 48 to insure good filling of the low pressure pump, especially at high rotative speeds. The high pressure pump is preferably provided with a considerable number of pistons which is desirable to reduce pressure pulsations, and the high pressure pump is pressurized by the low pressure pump to eliminate cavitation in the high pressure pump. The low pressure pump also eliminates the necessity of springs or linkage normally used for returning the pistons of the high pressure pump.

The vane pump ports 70 and 72, it will be noted, are axial to avoid pressure drop experienced with ports of the radial entry type. All of the pumping power transmitted to the rotating barrel is carried through concentric shafts which

are not subjected to any appreciable thrust. The pump is extremely compact, yet the parts are designed rugged enough for containing the high pressures generated.

- 5 With respect to the modified form shown in Figs. 15 and 16, increased pressure thrust of the barrel 44 against the end plate 18 is had by reducing the unseating pressure forces at the parting line between these two elements. This is 10 accomplished by reducing the circle diameter of the ports 58b, 82 and 84 in the novel manner disclosed. This also has the added advantage of reducing the circle diameter of the ports 82 and 84 and permitting the use of multiple passages 15 68 which are slightly increased in area at the ends thereof where they match the ports 82 and 84 by being drilled at a slant so as to be elliptical rather than truly round in cross-section at their terminal ends at the land 44b.
- 20 Some changes may be made in the construction and arrangement of the parts of our pump without departing from the real spirit and purpose of our invention, and it is our intention to cover by our claims any modified forms of structure or 25 use of mechanical equivalents which may be reasonably included within their scope.

We claim as our invention:

1. In a two-stage hydraulic pressure pump, a housing, a barrel drive shaft journaled therein, 30 a barrel loosely mounted on said shaft and operatively connected thereto, said barrel having cylindrical bores therethrough substantially parallel to the axis of rotation of the barrel, a piston in each of said bores, said barrel having 35 one of its ends seated against an end of said housing, cylinder ports in said end of said barrel and communicating with said cylindrical bores, a cam in said housing having a cam surface in the shape of a truncated cylinder end, said pistons 40 cooperating with said cam to effect sliding movement of the pistons in one direction upon rotation of said barrel, a low pressure vane pump rotor operatively connected with said barrel driving shaft and located within said cam, said cam being built to provide a stator chamber therefor, 45 said end of said housing having intake and discharge ports, and a passageway system leading from said intake port to said low pressure pump and from said low pressure pump to an intake 50 port in said housing end for said cylinder ports, and an outlet port in said housing communicating with said discharge ports.

2. In a two-stage hydraulic pressure pump, a housing, a barrel journaled therein and having cylindrical bores therethrough substantially parallel to the axis of rotation of the barrel, a piston in each of said bores, said barrel having 55 one of its ends seated against an end of said housing, cylinder ports in said end of said barrel and communicating with said cylindrical bores, a cam in said housing having a cam surface in the shape of a truncated cylinder end, said pistons 60 cooperating with said cam to effect sliding movement of the pistons in one direction upon rotation of said barrel, a low pressure vane pump having a rotor connected with said barrel for rotation therewith, said end of said housing having intake and discharge ports, a passageway system leading from said intake port to said low pressure pump and from said low pressure pump to an intake port in said housing end for 65 said cylinder ports, an outlet port in said housing end for said cylinder ports, and an outlet connection from said outlet port to said discharge port.
3. In a two-stage hydraulic pressure pump, a

housing, a barrel drive shaft journaled therein, a barrel mounted thereon, said barrel having cylindrical bores therethrough, a piston in each of said bores, said barrel having one of its ends seated against an end of said housing, cylinder ports in said end of said barrel and communicating with said cylindrical bores, a cam in said housing having a truncated cylinder end, said pistons cooperating with said cam end to effect sliding movement of the pistons in one direction upon rotation of said barrel, a low pressure pump operatively connected with said barrel driving shaft and located within said housing, said end of said housing having intake and discharge ports, and a passageway system leading from said intake port to said low pressure pump, from said low pressure pump to an intake port in said housing end for said cylinder ports, and from an outlet port in said housing end for said cylinder ports to said discharge port.

4. In a two-stage hydraulic pressure pump, a cylindrical housing, a barrel drive shaft journaled therein, a barrel on said shaft and having cylindrical bores therethrough substantially parallel to the axis of rotation of the barrel, a piston in each of said bores, said barrel having one of its ends seated against an end of said housing, cylinder ports in said end of said barrel and communicating with said cylindrical bores, a cam in said housing having a cam surface in the shape of a truncated cylinder end, said pistons cooperating with said cylinder end to effect sliding movement of the pistons in one direction upon rotation of said barrel, a low pressure vane pump operatively connected with said barrel driving shaft and located within said housing in end to end relation with said barrel and cam, said end of said housing having intake and discharge ports, and a passageway system leading along one side of said housing from said intake port to said low pressure pump, along the other side of said housing from said low pressure pump to an intake port in said housing end for said cylinder ports, and from an outlet port in said housing end for said cylinder ports to said discharge port.

5. In a hydraulic pressure pump, a housing, a barrel drive shaft journaled therein, a barrel on said shaft and operatively connected thereto for rotation therewith, said barrel having cylindrical bores, pistons in said bores, a cam for sliding said pistons in one direction, an end plate for said housing, said barrel having one of its ends seated thereagainst, cylinder ports in said end of said barrel, said end plate having a pump inlet and a pump outlet, a low pressure pump in said housing, said barrel and cylinders being located between said low pressure pump and said end plate, a passageway arrangement from said inlet through said housing to said low pressure pump, from said low pressure pump through said housing to said cylinder ports and from said cylinder ports to said outlet, and said passageway arrangement including dowels and a back plate having ports for said low pressure pump, said back plate being adjustable through 180° for permitting reversal of the rotation of said piston type and low pressure pumps and being rotatable when said dowels are removed, said dowels preventing rotation of said back plate when they are inserted in said housing, one of said dowels being coactable with said back plate in only a predetermined manner depending on the position of the back plate, and having a direction indicating element thereon to indicate the direction

of rotation depending upon the adjustment of the back plate.

6. In a hydraulic pressure pump, a housing, a barrel drive shaft journaled therein, a barrel mounted on said shaft, said barrel having cylindrical bores, pistons in said bores, a cam for sliding said pistons in one direction, an end plate for said housing, said barrel having one of its ends seated thereagainst, cylinder ports in said end of said barrel, said end plate having a pump inlet and a pump outlet, a low pressure pump in said housing, a passageway arrangement from said inlet to said low pressure pump, from said low pressure pump to said cylinder ports and from said cylinder ports to said outlet, said low pressure pump having a back plate which is adjustable through 180° for permitting reversal of the rotation of said piston type and low pressure pumps, and said passageway arrangement including hollow dowels for coaction with back plate to prevent rotation thereof when they are inserted in said housing.

7. In a hydraulic pressure pump a housing, a barrel mounted for rotation therein, said barrel having cylindrical bores, pistons in said bores, a cam for sliding said pistons in one direction, said barrel having one of its ends seated against an end of said housing, cylinder ports in said end of said housing, said housing having a pump inlet and a pump outlet, a low pressure pump in said housing, and a passageway arrangement from said inlet to said low pressure pump, from said low pressure pump to said cylinder ports and from said cylinder ports to said outlet, said low pressure pump including a plate adjustable through 180° for permitting reversal of the rotation of said piston type and low pressure pumps, said plate having ports for said low pressure pump.

8. In a hydraulic pressure pump, a housing, a barrel drive shaft journaled therein, a barrel loosely mounted on said shaft and operatively connected thereto for rotation therewith, said barrel having cylindrical bores, pistons in said bores, a cam for sliding said pistons in one direction, an end plate for said housing, said barrel having one of its ends seated thereagainst under pressure within the housing, cylinder ports in said end of said barrel, said end plate having a pump inlet and a pump outlet, a low pressure pump in said housing including a stator chamber formed in said cam, said barrel and cylinders being located between said stator and said end plate, a passageway arrangement from said inlet through said housing to said low pressure pump, from said low pressure pump to said cylinder ports and from said cylinder ports to said outlet, said low pressure pump having a ported back plate adjustable through 180° for permitting reversal of the rotation of said piston type and low pressure pumps, and said passageway arrangement including hollow dowels, said back plate being rotatable when said dowels are removed, and said dowels extending into said back plate and permitting rotation thereof when the dowels are inserted in said housing, one of said dowels being coactable with said back plate in only one predetermined manner when the back plate is in one position and in another predetermined manner when the back plate is in its other position to indicate the direction of rotation for the pump.

9. In a two-stage hydraulic pressure pump, a housing, an end plate therefor, a barrel, mounted for rotation, in said housing, a cam, a low pres-

sure pump and a back plate arranged in series in said housing, said barrel having a plurality of reciprocable pistons, said barrel, cam and pistons constituting a high pressure pump, a drive shaft for said barrel and said low pressure pump, said end plate having inlet and outlet ports therefor, said low pressure pump being adaptable for charging said high pressure pump, said end plate having a pump inlet and a pump outlet, a passageway arrangement from said pump inlet to said back plate, said back plate having inlet and outlet ports for said low pressure pump, said last passageway leading to said last inlet port, said passageway arrangement extending from the outlet port in said back plate to the inlet port in said end plate and the outlet port of said end plate extending to said pump outlet, said back plate being rotatable through a 180° arc for permitting reversal of the rotation of said low pressure and high pressure pumps, and a sealing means between said drive shaft for said pumps and said housing, said sealing means being located beyond said back plate.

10. In a two-stage hydraulic pressure pump, a housing, an end plate therefor, a barrel mounted for rotation in said housing, a cam, a low pressure pump and a back plate arranged in series in said housing, said barrel having a plurality of reciprocable pistons, said barrel, cam and pistons constituting a high pressure pump, said end plate having inlet and outlet ports therefor, said low pressure pump being adaptable for charging said high pressure pump, said end plate having a pump inlet and a pump outlet, a passageway arrangement from said pump inlet to said back plate, said back plate having inlet and outlet ports for said low pressure pump, said last passageway leading to said last inlet port, said passageway arrangement extending from the outlet port in said back plate to the inlet port in said end plate and the outlet port of said end plate extending to said pump outlet, said back plate being rotatable through a 180° arc for permitting reversal of the rotation of said low pressure and high pressure pumps.

11. In a two-stage hydraulic pressure pump, a housing, an end plate therefor, a barrel rotatably mounted in said housing, a cam, a low pressure pump and a back plate in said housing, said barrel having a plurality of reciprocable pistons, said barrel, cam and pistons constituting a high pressure pump, said end plate having inlet and outlet ports therefor, said end plate having a pump inlet and a pump outlet, a passageway arrangement from said pump inlet to said back plate, said back plate having inlet and outlet ports for said low pressure pump, said last passageway leading to said last inlet port, said passageway arrangement extending from the outlet port in said back plate to the inlet port in said end plate and the outlet port of said end plate extending to said pump outlet, said back plate being rotatable through a half revolution for permitting reversal of the rotation of said low pressure and high pressure pumps.

12. In a two-stage hydraulic pressure pump, a housing, an end plate therefor, a barrel rotatably mounted in said housing, a cam, a low pressure pump and a back plate arranged in series in said housing, said barrel having a plurality of reciprocable pistons, said barrel, cam and pistons constituting a high pressure pump, said end plate having inlet and outlet ports therefor, said end plate having a pump inlet and a pump outlet, a passageway arrangement from

5 said pump inlet to said back plate, said back plate having inlet and outlet ports for said low pressure pump, said last passageway leading to said last inlet port, said passageway arrangement extending from the outlet port in said back plate to the inlet port in said end plate and the outlet port of said end plate extending to said pump outlet.

13. In a pressure pump of the character disclosed, a housing, an end plate therefor, a barrel mounted for rotation in said housing, a cam, a low pressure pump and a back plate arranged in series in said housing, said barrel having a plurality of reciprocable pistons, said barrel, cam and pistons constituting a high pressure pump, said end plate having inlet and outlet ports therefor, said low pressure pump being adaptable for overcharging said high pressure pump, said end plate having a pump inlet and a pump outlet, a passageway arrangement from said pump inlet to said back plate, said back plate having inlet and outlet ports for said low pressure pump, said last passageway leading to said last inlet port, said passageway arrangement extending from the outlet port in said back plate to the inlet port in said end plate and the outlet port of said end plate extending to said pump outlet, said back plate and said cam being rotatable through 180° for permitting reversal of the rotation of said low pressure and high pressure pumps, and said passageway arrangement including hollow dowels extending radially into said housing and said back plate and communicating with the low pressure pump inlet and outlet ports thereof.

14. In a hydraulic pressure pump of two-stage character, a housing, a barrel driving shaft journaled therein, a barrel loosely mounted on said shaft, an end plate for said housing, said barrel having a plurality of cylinder bores, said barrel being engaged with said end plate under fluid pressure against partially closed ends of said cylinder bores, pistons in said cylinder bores, a cam for sliding said pistons in one direction, a low pressure pump, said end plate having inlet and outlet ports for said cylinder bores, said low pressure pump charging said inlet port, said end plate having an intake and an outlet, said intake charging said low pressure pump and said outlet port charging said outlet of said end plate.

15. In a two-stage hydraulic pressure pump, a housing, a barrel rotatably mounted therein, an end plate for said housing, said barrel being engaged therewith and having a plurality of cylinder bores, pistons therein, a cam for sliding said pistons in one direction, a low pressure pump for charging said pistons with fluid, said end plate having inlet and outlet ports for said cylinder bores, said end plate having an intake and an outlet, said intake charging said low pressure pump and said outlet of said end plate.

16. In a pump structure of the character disclosed, a cylindrical housing, an end plate thereon, a barrel against said end plate and having cylinder bores, pistons in said bores, a cam for sliding said pistons in one direction when said barrel is rotated, a sliding vane type pump in said housing next to said cam, a back plate thereadjacent, said back plate being adjustable through 180° for permitting reversal of the rotation of said piston and vane type pumps, said end plate having an inlet and an outlet, and a passageway arrangement from said inlet through said back plate to said vane pump, from

said vane pump to said cylinder and piston pump, and from said cylinder and piston pump to said outlet of said end plate, said passageway arrangement including dowels removably positioned in said housing for retaining said back plate against rotation, said dowels being removable to permit adjustment of the back plate and vane pump, and one of said dowels so coacting with said back plate in such manner that the direction of rotation can be determined thereby. 10

17. In a pump structure of the character disclosed, a cylindrical housing, an end plate thereon, a barrel against said end plate and having cylinder bores, pistons in said bores, means for sliding said pistons in one direction when said barrel is rotated, a sliding vane type pump in said housing, a back plate thereadjacent, said back plate being adjustable through 180° for permitting reversal of the rotation of said piston and vane type pumps, said end plate having an 15

inlet and an outlet, and a passageway arrangement from said inlet through said back plate to said vane pump, from said vane pump to said cylinder and piston pump, and from said cylinder and piston pump to said outlet of said end plate. 5
